EDWARD ZAHM, OF BUFFALO, NEW YORK.

LIQUID-DISPENSING APPARATUS.

1,273,021.

Specification of Letters Patent. Patented July 16, 1918.

Application filed January 22, 1915, Serial No. 3,709. Renewed June 5, 1918. Serial No. 238,393.

To all whom it may concern:

Be it known that I, EDWARD ZAHM, a citizen of the United States, residing at Buffalo, in the county of Erie and State of New York, have invented new and useful Improvements in Liquid-Dispensing Apparatus, of which the following is a specification.

This invention relates to an apparatus for serving or dispensing liquids containing gas, such as beer, although the same may also be used for dispensing other liquids.

It is the object of this invention to provide an apparatus for this purpose in which a constant fluid pressure is maintained upon the liquid in the dispensing tank regardless of any fluctuation of the height of the liquid in the same and also regardless of the difference in elevation between the supply barrel and the dispensing tank for the purpose of preventing undue foaming of the beer, whereby the gas is uniformly retained throughout the entire mass of beer at all times, so that no part of the same is flat, it being the further object of this invention to accomplish this result without reducing the pressure upon the beer while changing the tapping connections from an empty supply barrel to a full supply barrel and also to cause a signal to be given when the supply of beer is exhausted and requires replenishing.

In the accompanying drawings:

Figure 1 is a sectional elevation of a beer dispensing apparatus embodying my invention. Fig. 2 is a vertical section, on an enlarged scale, of the dispensing tank or chamber and the parts associated therewith. Figs. 3 and 4 are horizontal sections taken in the correspondingly numbered lines in

Fig. 2.

Similar characters of reference indicate corresponding parts throughout the several views.

1, 2 represent two barrels or containers which are adapted to hold a supply of beer or other liquid containing gas as well as liquids containing no gas and which are usually arranged in the cellar of the building or other place which is lower than that where the liquid is to be dispensed. 3 represents a dispensing or serving tank or chamber arranged at a higher elevation than the supply barrels, for instance, behind a bar or serving stand 4 which is arranged in

a room on the ground floor of the building. A fluid pressure is produced on top of the liquid in the supply barrels for the purpose of forcing it out of the same into the dispensing tank which pressure may be produced by carbonic acid gas or other fluid under pressure which is introduced into the upper ends of the barrels through pipes 5, 5 each having a controlling valve 6. The liquid in the supply barrels is discharged from the lower ends thereof through tapping pipes or tubular rods 7 having their inlet ends arranged adjacent to the bottoms of these barrels while their discharge ends are connected by branch transfer pipes 8, 9 with a main transfer 10 opening into the upper end of the dispensing chamber or tank so that the liquid expelled from one or the other of the supply barrels enters the dispensing tank at the upper end thereof. The branch transfer pipes 8, 9 are provided, respectively, with valves 11, 12, whereby either one or the other of the supply barrels may be connected with the dispensing tank, thereby permitting of cutting off an empty barrel from the dispensing system and cutting in a full barrel and thereby enabling the serving of the liquid to proceed without interruption. The dispensing tank is preferably arranged in a box 13 containing ice which surrounds the dispensing tank for the purpose of keeping the contents thereof cool, and the liquid is withdrawn from the lower end of this tank by one or more dispensing or serving pipes 90 leading to valves under the control of the attendant. As shown in the drawings, two of such pipes 14, 15 extend from the lower end of the dispensing tank upwardly to different places along the top or table of the bar and provided respectively with serving faucets, valves or spigots 16, 17, so that either one or two bar tenders can draw beer or a similar liquid from the dispensing tank at the same time.

My improvements which are added to the parts of the liquid dispensing system just described for the purpose of maintaining a substantially uniform pressure on the liquid and avoiding undue foaming or flattening of the same and also to give a warning signal in case the supply of beer is exhausted is constructed as follows:

18 represents a cylindrical wall rising from the top or head 19 which is removably

secured to the upper end of the dispensing tank and 20 a flexible diaphragm arranged on the upper end of this wall so as to form a controlling chamber 21 between this wall, 5 diaphragm and the adjacent part of the tank head. 22 represents an upwardly dished dome engaging its marginal part against the edge of the diaphragm and forming with the latter a relief or signal chamber 23. The edge of the diaphragm is secured between the upper edge of the wall 18 and the lower edge of the dome by screws 24, as shown in Fig. 2, or by any other suitable 10 means so that leakage through the joint between the diaphragm, wall and dome is prevented.

25 represents a boss projecting downwardly from the under side of the upper tank head preferably on the central part thereof and provided with a passage or port which preferably comprises a vertical lower part 26 opening into the tank and terminating at its lower end in a valve seat 28, and two upper inclined parts 27 diverging upwardly from the upper end of the vertical lower part and opening into the controlling chamber on opposite sides of an upwardly projecting boss 29 arranged centrally on the upper side of the upper tank head 22.

30 represents a controlling valve preferably of spherical form which is adapted to move vertically toward and from the valve seat 28 for the purpose of closing or opening the passage or port 26, 27 leading from the 35 upper part of the dispensing tank to the controlling chamber. The movement of the controlling valve for opening or closing the controlling passage 26, 27 is effected by the rise and fall of the liquid level in the dispensing tank for which purpose a float or 40 buoyant member 31 is arranged in the dispensing tank and connected on its upper side with the lower side of the controlling valve by means of a vertical valve stem 32.

45 As the liquid level in the dispensing tank rises above a certain level the float is elevated and causes the controlling valve to be pressed against its companion seat 28 so that the passage 26, 27 is closed and when the liquid

50 level in this tank drops below a certain point or elevation the float drops and carries the controlling valve downwardly away from its seat, so that the controlling passage is opened and communication is established between 55 the upper end of the dispensing tank and the controlling chamber. The controlling valve and float are guided in their vertical movements preferably, by means of a cage comprising a plurality of upright supporting bars 33 arranged on opposite sides of the valve stem 32, a supporting ring 34 arranged at the upper end of these bars and having a screw connection with the lower end of the lower boss 25 and a plurality of 60 cross bars 35 connecting the upright bars

and provided centrally with openings in which the valve stem 32 is guided in its vertical movements.

When the controlling valve is lowered by the dropping of the float due to a lowering 70 of the liquid level in the dispensing tank and the upper end of the latter is placed in communication with the controlling chamber the fluid pressure in the latter rises to that in the dispensing tank. This communication between the dispensing tank and the controlling chamber has no effect on the operation of the apparatus up to a predetermined pressure but if the pressure in the controlling chamber should exceed a predetermined limit then the diaphragm will be raised and permit the pressure fluid to escape from the controlling chamber this 80 escaping pressure fluid being preferably, though not necessarily, used for operating a signal. This abnormally high pressure in the controlling chamber and dispensing tank occurs when the barrel which supplies the liquid is exhausted and the hydrostatic-head of the liquid in the piping between the 90 supply barrel and the dispensing tank has been removed so that now the full pressure of the fluid supplied to the respective supply barrel enters the dispensing tank and controlling chamber instead of being reduced 95 by the resistance which is offered by the hydrostatic-head in the transfer piping extending from the supply barrel to the dispensing tank. The signal thus given serves as a warning to the attendant that a new or 100 full barrel of beer must be connected with the dispensing system. In its preferred form this signal consists of a whistle 36 which is mounted on the dome and communicates with the interior of the relief chamber 105 and a valve mechanism is provided whereby communication is established between the controlling chamber and the relief chamber when the diaphragm is deflected upwardly by a pressure which exceeds a predetermined limit. This signal valve mechanism may be constructed in various ways that shown in the drawings being suitable for the purpose and constructed as follows:

37 represents an upright relief valve secured centrally to the diaphragm and having its lower part projecting downwardly from the underside of the diaphragm and terminating at its lower end in a valve face 38. The latter is adapted to move toward and from a packing 39 arranged on the upper end of the boss 29 and forming a valve seat for said relief valve. This packing may be secured against the upper end of this boss 29 in any suitable manner but preferably by a retaining sleeve 40 having a screw connection with this boss and provided with an inwardly projecting flange 41 forming an internal shoulder which bears against the upper side of the valve packing and also with 110 115 120 125 130

an annular row of upwardly projecting guide lugs 42 which surround the lower end of the valve and form a guide for the latter in its movement toward and from its companion valve seat. The upper end of the valve projects upwardly from the diaphragm and is guided in a collar 43 formed centrally on the upper side of the dome. 44 represents a relief passage arranged in the relief valve 10 and opening at its lower end in the face of the valve while its upper end opens laterally through this valve into the relief chamber. So long as the face of the relief valve bears against the seat 39 communication between the controlling chamber and the relief chamber is cut off and the whistle will not be sounded, but when the diaphragm is raised and the relief valve is lifted from its seat then the fluid under pressure in the controlling chamber will pass upwardly through the relief passage 44 into the relief chamber and then through the whistle into the outer atmosphere so that an audible signal is given. Means are provided for yieldingly resisting the upward movement of the diaphragm and permit of varying the degree of this resistance and therefore enable the time of opening of the relief valve to be set accordingly to a predetermined pressure. In its preferred form this adjustable resistance means comprises a supporting tube 45 secured at its lower end to the collar 43 of the dome and provided at its upper end 35 with an adjusting screw 46 projecting downwardly into this tube, and a tension spring 47 arranged within the supporting tube and bearing at its upper and lower ends through the medium and lower disk 48, 49 against the lower end of the adjusting screw and the upper end of the relief valve. By adjusting the screw 46 up or down the tension of the spring 47 may be varied in accordance with the predetermined pressure under which the diaphragm 45 should yield to the upward pressure of the fluid in the controlling chamber for opening a relief valve.

Assuming that a fluid pressure of, say 15 pounds, is introduced into the respective supply barrel from which the liquid is being withdrawn and that the frictional and hydrostatic resistance of the liquid contained in the piping leading from the supply barrel to the dispensing chamber or tank is equivalent to 9 pounds there would be a fluid pressure exerted upon the liquid in the dispensing tank amounting to 6 pounds under the normal operation of the apparatus. The tension of the means which resist the upward movement of the diaphragm and the opening of the relief valve under these circumstances would be so adjusted that this diaphragm will only be lifted and the relief valve opened when

the pressure in the dispensing tank and the controlling chamber exceed this normal pressure of 6 pounds. For this purpose it will be assumed that the tension spring is so set that this relief valve will open below a pressure of 6 pounds say at a pressure of five pounds against the underside of the diaphragm. This differential of one pound between the pressure at which the liquid enters the dispensing tank 3 and the pressure at which the relief valve 38 is set compensates for any compression of gas in the upper part of the tank 3 and any fluctuation in the counter-pressure in the tank which controls the flow of liquid into the tank 3 through the pipe 10 between the time that the liquid flows out of the tank 3 upon opening a tap and the time the outflow is arrested upon closing the tap. Under these circumstances the liquid will be discharged from the dispensing tank under a pressure of say 6 pounds through one or both of the serving spigots when the latter are opened and the liquid in the dispensing tank will be constantly replenished from the supply barrel by reason of the fluid pressure of 15 pounds against the contents in the latter. Normally when the liquid is only withdrawn from the dispensing tank at a moderate rate, for instance when only one of the spigots is in use at a time and at comparatively long intervals the transfer of the liquid from the supply barrel to the dispensing tank will keep pace with the amount of liquid withdrawn from the latter through the spigot, so that the dispensing tank will remain nearly full and the level of the liquid will remain normally at such a height that the float will be caused to hold the controlling valve in its closed position and cut off communication between the dispensing tank and the controlling chamber. When, however, the liquid is withdrawn from the dispensing tank more rapidly than the rate at which the same is replenished from the supply barrel which is liable to occur when one spigot is employed very frequently or more than one spigot is used at the same time, then the float will drop below its normal position in response to the lowering of the level of the liquid in the dispensing tank below the normal and thereby open the controlling valve and placing the dispensing tank in communication with the controlling chamber and at the same time the pressure in the dispensing tank will drop somewhat, say more than 1 pound, so that the relief valve 38 remains shut. When, however, the liquid level again rises to the normal position in the dispensing tank the float will again rise and cause the controlling valve to close the controlling passage. When the controlling valve is opened under these conditions no effect is produced which alters the normal

operation of the apparatus inasmuch as the entering of the pressure fluid from the dispensing tank into the controlling chamber under a pressure of less than 5 pounds will 5 not be able to raise the diaphragm and the relief valve will remain closed inasmuch as the tension spring has been set so that it will only yield under a pressure of 5 pounds or more under which circumstances there 10 would be a differential of 1 pound to allow the fluctuations between the normal pressure of 6 pounds in the dispensing tank and the tension of 5 pounds at which the relief valve 38 is held shut by its spring.

15 When all the beer possible has been discharged from the supply barrel into the dispensing tank and the transfer pipe between the barrel and tank has also been emptied so that the hydrostatic-head of the 20 liquid in the transfer pipe no longer opposes the pressure of 15 pounds in the supply barrel then this full pressure with the exception of a slight frictional resistance in the transfer pipes, will enter the upper end 25 of the dispensing tank and also pass from the latter into the controlling chamber when the liquid level in the latter drops to such an extent that the float opens the controlling valve. This abnormal pressure being in excess of the 5 pounds resistance offered by the 30 tension spring 47 will cause the diaphragm to be lifted and the relief valve to be opened so that this pressure fluid now passes through the passage or port in the relief valve into the relief chamber and out through the whistle so that the latter is sounded and the attendant is notified that a new barrel of beer must be tapped. The 35 attendant now shuts off the valve of that branch transfer pipe communicating with the empty supply barrel and opens the valve of the branch transfer pipe leading to the full supply barrel. When this occurs the 40 pressure of the fluid from the pipe 5 upon the liquid in the last mentioned barrel will force this liquid through the last mentioned branch transfer pipe into the dispensing tank and when this transfer pipe has been 45 filled with liquid and the hydrostatic head 50 or resistance of the liquid therein again opposes this pressure of the fluid in the main pressure pipe 5 then the fluid pressure in the dispensing tank is again reduced say below the normal pressure of 5 pounds, thereby permitting the tension 55 spring which exerts a pressure of 5 pounds to again close the relief valve and stop the further escape of pressure fluid through the whistle and arresting the sounding of the latter. After the relief valve has been thus 60 closed by the pressure of its spring the continued in-flow causes the dispensing tank 3 to gradually become filled so that the liquid 65 eventually lifts the float 30 and closes the float valve 31. After the float valve is closed

the liquid continues to flow into the tank 3 until a pressure of 6 pounds has been built up in the same which operates to stop the further flow of liquid from the container or barrel 1 or 2 into the tank or receiver 3. 70

After this transfer of the connections of the dispensing tank from the empty supply barrel to the full barrel the pressure upon the liquid in the dispensing tank is maintained at 6 pounds. It is therefore impossible for the pressure in the dispensing tank to drop so low that the beer would be transferred in a foamy condition from the supply barrel to the dispensing tank. If the pressure fluid in the dispensing tank were permitted to escape to the atmosphere so that but little or no pressure remained in the dispensing tank to oppose the entrance of the liquid into this tank after transferring the connections of the tank from one barrel to another the rush of the liquid under pressure from the supply barrel into the discharge tank which would not be under a pressure sufficient to maintain the gases in solution, would cause 80 liberation of the gases and result in a large quantity of flat liquid being dispensed before a normal condition is again established. This objection is avoided in this dispensing apparatus inasmuch as sufficient pressure is 85 maintained on the beer in the dispensing tank to prevent an unduly rapid flow or rush of liquid from the supply barrel to the dispensing tank under all conditions and thereby maintain the beer or other liquid in 90 a condition in which the gas is uniformly distributed throughout the entire mass of beer and the same is maintained in its most palatable condition. 95

From the foregoing it will be obvious that 100 in this process of dispensing liquids containing gas, a pressure is constantly maintained in the dispensing tank which is less than the ultimate effect of the pressure employed for forcing the liquid from the supply barrel or original container, minus the hydrostatic-head and frictional resistance represented by the liquid in the piping extending from the supply barrel to the dispensing tank. 105

I claim as my invention:

1. A liquid dispensing apparatus comprising a tank having a liquid inlet and a liquid outlet, a controlling chamber connected with said tank by a controlling passage and having a diaphragm exposed to the pressure in said chamber and a vent passage, a controlling valve adapted to open and close said controlling passage, a float arranged in said tank and operating said controlling valve, and a valve which opens and closes said vent passage and which is operated by said diaphragm. 110

2. A liquid dispensing apparatus comprising a tank having a liquid inlet and a liquid 115

outlet, a controlling chamber connected with said tank by a controlling passage and having a diaphragm exposed to the pressure in said chamber and a vent passage, a controlling valve adapted to open and close said controlling passage, a float arranged in said tank and operating said controlling valve, a valve which opens and closes said vent passage and which is operated by said diaphragm, and a whistle which is blown by the fluid escaping from said relief passage.

3. A liquid dispensing apparatus comprising a tank having a liquid inlet and a liquid outlet, a controlling chamber connected with said tank by a controlling passage and having a diaphragm exposed to the pressure in said chamber and a vent passage, a controlling valve adapted to open and close said controlling passage, a float arranged in said tank and operating said controlling valve, a valve which opens and closes said vent passage and which is operated by said diaphragm, and a spring for yieldingly moving said diaphragm in a direction for closing said relief valve.

4. A liquid dispensing apparatus comprising a tank having a liquid inlet and a liquid outlet, a controlling chamber connected with said tank by a controlling passage and having a diaphragm exposed to the pressure in said chamber and a vent passage, a controlling valve adapted to open and close said controlling passage, a float arranged in said tank and operating said controlling valve, a valve which opens and closes said vent passage and which is operated by said diaphragm, a spring for yieldingly moving said diaphragm in a direction for closing said relief valve, and means for adjusting the tension of said spring.

5. A liquid dispensing apparatus comprising a tank having a liquid inlet and a liquid outlet, a controlling chamber connected with said tank by a controlling passage and having a diaphragm exposed to the pressure in said chamber and a vent passage, a controlling valve adapted to open and close said controlling passage, a float arranged in said tank and operating said controlling valve, a valve which opens and closes said vent passage and which is operated by said diaphragm, a spring for yieldingly moving said diaphragm in a direction for closing said relief valve, means for adjusting the tension of said spring, and a whistle which is blown by the fluid escaping from said relief passage.

6. A liquid dispensing apparatus comprising a tank having an inlet and an outlet for the liquid, a controlling chamber arranged on said tank and communicating with the latter by a controlling passage, a float arranged in said tank, a controlling valve moving with said float and opening

and closing said controlling passage, a relief chamber arranged adjacent to the controlling chamber, said controlling and relief chambers being separated by a diaphragm, a relief valve mounted on said diaphragm and provided on its inner end with a face movable toward and from a seat in the controlling chamber and having a passage leading from said face in the controlling chamber to the relief chamber, and a whistle communicating with the relief chamber.

7. A liquid dispensing apparatus comprising a tank having an inlet and an outlet for the liquid, a controlling chamber arranged on said tank and communicating with the latter by a controlling passage, a float arranged in said tank, a controlling valve moving with said float and opening and closing said controlling passage, a relief chamber arranged adjacent to the controlling chamber, said controlling and relief chambers being separated by a diaphragm, a relief valve mounted on said diaphragm and provided on its inner end with a face movable toward and from a seat in the controlling chamber and having a passage leading from said face in the controlling chamber to the relief chamber, and a spring operating on said diaphragm to hold the relief valve yieldingly against said seat.

8. A liquid dispensing apparatus comprising a tank having an inlet and an outlet for the liquid, a controlling chamber arranged on said tank and communicating with the latter by a controlling passage, a float arranged in said tank, a controlling valve moving with said float and opening and closing said controlling passage, a relief chamber arranged adjacent to the controlling chamber, said controlling and relief chambers being separated by a diaphragm, a relief valve mounted on said diaphragm and provided on its inner end with a face movable toward and from a seat in the controlling chamber and having a passage leading from said face in the controlling chamber to the relief chamber, a guide on the outer side of said relief chamber which receives the outer end of said relief valve, a supporting tube mounted at its inner end on said relief chamber, an adjusting screw arranged on said tube, and a spring interposed between the inner end of the screw and the outer end of said relief valve.

9. A liquid dispensing apparatus comprising a tank having an inlet and an outlet for the liquid, an inwardly projecting boss containing a controlling passage opening into the tank, a controlling chamber which is arranged on the outer side of said tank and into which said controlling passage opens, an outer boss arranged on the outer side of the tank within the controlling chamber, a valve seat arranged on said outer boss, a sleeve having a screw connection with said

6
outer boss and provided with an internal shoulder bearing against said seat and with a plurality of guide lugs around said seat, a diaphragm subject to the internal fluid 5 pressure with said controlling chamber, and a valve mounted on said diaphragm and having its inner end guided between said lugs and provided with a face movable toward and from said seat and having a relief 10 passage leading from said face to the outer side of said diaphragm.

10. An apparatus for dispensing gas containing liquids comprising a liquid chamber having a liquid inlet and a liquid outlet 15 and a gas outlet in its upper part, a

liquid operated valve for the inner part of said gas outlet which is responsive to variations in the level of the liquid in said chamber, and a gas operated relief for the outer part of said gas outlet which is responsive to variations of the gas pressure in said chamber when said liquid operated valve is open. 20

Witness my hand this 19th day of January, 1915.
